DEVICE FOR PRODUCING SIGNALS AT
PREDETERMINED INTERVALS

Max E. Snoddy, Dallas, Tex.

Application January 30, 1952, Serial No. 269,079

13 Claims. (Cl. 161—1)

1

This invention relates to a time control device and more particularly to a time control device for producing a signal of relatively short duration at a predetermined time.

In many applications, such as in apparatus for the irrigation of lawns, it is necessary that a signal of split second duration be transmitted to the apparatus at a particular time of the day to initiate its operation. A device for producing such a signal should be of simple construction, accurate in operation, and easy to set.

Accordingly, it is an object of the invention to provide a new and improved device for providing a signal of short duration at a predetermined time.

It is another object of the invention to provide a new and improved clock operated device for providing a signal at a predetermined time of the day.

It is still another object of the invention to provide a new and improved control device of simple rugged construction for producing a signal at a predetermined time.

Briefly stated, the new and improved device for producing a signal at a predetermined time includes a clock motor which rotates a dial on which is fastened a trip arm. The trip arm contacts a rotatable cam and causes it to rotate. A bridge connected to the cam for movement with the cam in one direction maintains the lever arm of a micro-switch in inoperative position until shortly before the trip arm disengages from the cam to release it for movement to its old position. The bridge is held by the lever arm after the cam commences to move back to its original position to permit the lever arm to move to actuating position in which the micro-switch is closed for a short period of time, the cam camming the lever arm back to non-actuating as it rotates back to its old position. A wheel is geared to the cam to retard the speed of rotation of the cam to its old position.

For a better understanding of the invention, reference may be had to the following description taken in connection with the accompanying drawing and its scope will be pointed out in the appended claims.

In the drawing,

Figure 1 is a front plan view of the control device;

Figure 2 is a vertical sectional view taken on the line 2—2 of Figure 1;

Figure 3 is a front plan view showing the graduations on the dial;

Figure 4 is a sectional view taken on line 4—4 of Figure 1;

2

Figure 5 is an enlarged fragmentary plan view showing the cam, the toggle and the lever arm in two different operative positions; and

Figure 6 is a perspective view showing the cam, the toggle and a portion of the lever arm in their normal or rest positions.

Referring now to the drawing, a conventional electric clock motor 10 provided with the usual speed reducing gear train 11 is mounted on a supporting plate 12 by means of a spacing block 13 and screws 14. The drive shaft 15 driven by the motor and gear train extends into a bore 16 in a main shaft 17. The frictional engagement of the drive shaft and the walls of the bore cause the main shaft to rotate with the drive shaft.

The main shaft 17 is journaled in a bearing sleeve 18 which has a reduced threaded portion 19 and an annular shoulder 20. The annular shoulder abuts the front side of the supporting plate 12 and the reduced threaded portion extends through an aperture in the supporting plate and is held in position by a washer 21 which bears against the rear side of the supporting plate and a nut 22 threaded on the threaded portion.

A dial 23 is fastened onto a knob 24 which is rigidly secured on the outer end of the main shaft 17 by a set screw 25. The dial is prevented from slipping on the knob by a pin 24a which extends through the dial into the knob. The dial may be marked off in 24 divisions indicating the twenty-four hours of the day or it may be marked off into 48 divisions to indicate forty-eight hours if the gear train 11 is such as to cause the dial to complete a revolution once every two days.

A sleeve 26 is rotatably mounted on the main shaft between the dial 23 and the outer end of the bearing sleeve and has a reduced portion 27 forming an annular shoulder 28. A trip arm 29 is mounted on the rotatable sleeve 26 and its lower end bears against the annular shoulder 28. The outer end 29 of the trip arm is bent over the outer edge of the dial and is cut away to produce a pointer 30. A screw 31 extends through an aperture in the bent outer end 29 into a threaded aperture in the trip arm to clamp the trip arm at any desired position on the dial. The trip arm rotates with the dial.

A portion of the trip arm is bent back, as at 32, to form a leg 33 which extends rearwardly toward the supporting plate 12 to engage the radially extending surface 34 of a cam 35. The cam 35 is rigidly mounted on a sleeve 36 which is rotatably mounted on the supporting plate 12. The sleeve is rotatably mounted on a post 39 which has a reduced threaded portion 40 which extends through an aperture in the supporting plate and

is held therein by a washer 41 and a nut 42. The post 39 has an outer annular flange 43 so that the sleeve 38 is held between the flange 43 and the front side of the supporting plate.

The cam is biased toward the position shown in Figure 1 by a spring 44 disposed about the sleeve 38 and having one end 45 rigidly secured to the sleeve and the other to a post 46 threaded in an aperture in the supporting plate. The post 46 extends outwardly to limit the movement of the cam in a clockwise direction, Figure 1, since the surface 34 of the cam will engage it.

The sleeve 38 is also provided with a pair of flanges 47 and 48 between which is received the arcuately cut-away inner end of the bridge 49. The bridge has two legs 50 and 51 which extend on opposite sides of the sleeve. The bridge is pivotable about the sleeve.

The cam 35 is provided with an arcuate slot 52 through which extends a screw 53. The screw 53 is threaded in a tapped aperture in the bridge and extends therethrough so that one end of a biasing spring 54 may be secured thereto. The other end of the spring 54 is secured to a screw 55 threaded in a suitable aperture in the supporting plate 12. The spring 54 biases the bridge in a clockwise direction, Figure 1.

The outer arcuate peripheral surface 56 of the bridge extends from a point where it is flush with the outer peripheral arcuate surface 57 of the cam to a point where it extends beyond it as at 58 when both bridge and cam are in their normal rest positions. The cam 35 is cut-away at its periphery to provide a recess 59 having a substantially arcuate surface 60 from which an inclined surface 61 extends to the arcuate peripheral surface 57.

The bent end 62 of the lever arm 63 of a micro-switch 64 contacts the bridge and the cam and is actuated thereby to close or open the micro-switch for a very short period of time. The micro-switch is secured to the supporting plate 12 by screws 65.

In use, the trip arm 29 is clamped on the dial at any desired position by the screw, the pointer 30 indicating the time at which the micro-switch will be actuated. The clock 19 and gear train 11 are of the type which allow the driving shaft 15 to rotate freely in a clockwise direction, Figure 1, but not in the opposite direction. The dial, therefore, can be rotated to set it in proper position with respect to the actual time of the day. The cam 35 and bridge 49 are now in the positions shown in Figure 1 in which the spring 44 biases the cam 35 toward the post 46 which limits its clockwise movement. The bridge is also biased in a clockwise direction by the spring 54 but its movement is limited by the abutment of the screw 53 with the lower end of the slot 52 in the cam. The bent end 62 of the lever arm 63 abuts the outer peripheral surfaces 57 and 56 of the cam and bridge and is biased against them since the conventional micro-switch provides a spring bias.

As the clock motor rotates, the drive shaft 15 and the dial are rotated in a clockwise direction and the leg 33 of the trip arm finally contacts the radially extending surface 34 of the cam. Further continuous rotation of the dial causes the trip arm to rotate the cam in a counterclockwise direction against the resistance of the springs 44 and 54. The bridge is also caused to rotate or pivot in a counter-clockwise direction since the lower edge of the slot 52 contacts the screw 53. During this counter-clockwise movement, the

bent arm 62 rides first on both peripheral surfaces 57 and 56 and then, as the recess 59 portion of the cam rotates past the bent end, only on the peripheral surface of the bridge.

Eventually, the cam and recess are rotated to the full line position shown in Figure 5 in which the bent end 62 has ridden off the peripheral surface of the bridge and now rests on the peripheral surface 66 of the cam on the opposite side of the recess from the peripheral surface 57. The radius of the peripheral surface 66 is slightly less than the radius of the peripheral surfaces 56 and 57.

Further rotation of the dial causes the leg 33 of the trip arm to ride past and disengage from the radially extending surface 34 of the cam, freeing the cam to return to its original position. As the cam rotates back in a clockwise direction, the bent end 62 engages the notched side 67 of the bridge and prevents it from also rotating in a clockwise direction. The bent end 62 moves inward and rides on the arcuate surface 60 of the recess. When the bent end 62 of the lever arm 63 is in this extreme position, the micro-switch 64 is closed or opened as the case may be and a signal is thus created. As the cam continues to rotate in a clockwise direction, the inclined surface 61 engages the bent arm and moves the bent arm outwardly until it is finally moved outwardly of the peripheral surface 56 of the bridge and out of engagement with the notched side 67 of the bridge. The bridge then moves in a clockwise direction back to the position shown in Figure 1. The cycle of operation is then repeated the next day to again make a signal at the predetermined time. It will be apparent that the micro-switch is connected in some control circuit so that when it is opened or closed, as the case may be, the control circuit causes some event to take place.

In order that the lever arm have sufficient time to move inwardly into the recess 59, the clockwise movement of the cam is retarded by a wheel 68 having a pinion gear 69 which meshes with the teeth 70 on the cam. The wheel 68 is rotatably mounted on the supporting panel by a post 71 having a reduced end 72 threaded in a tapped hole in the supporting plate 12. The inertia of the wheel 68 slows down the movement of the cam so that the lever arm of the micro-switch has sufficient time to move to actuated position before the recess 59 moves past the bent end 62 of the lever arm.

It will be apparent now that even though the dial rotates very slowly, the coaction of the cam and toggle enable the micro-switch to be actuated for a very short period of time to make a signal of very short duration. Moreover, it will be seen that the time control device can be easily set to produce the signal at any predetermined time of the day and that it is of simple rugged construction.

While a preferred embodiment of the invention has been illustrated and described, it will be apparent that various changes and modifications can be made without departing from the invention, and it is intended, therefore, in the appended claims to cover all such changes and modifications as fall within the true spirit and scope of the invention.

What is claimed is:

1. In a device of the type described, a dial; means for rotating said dial at a constant speed; a trip arm adjustably secured to said dial for rotation therewith; a cam rotatably mounted for

movement about an axis; a bridge mounted for movement about said axis, said cam and said bridge being connected for simultaneous movement in one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite direction, said recess having a camming surface to move said lever back to non-actuated position as said cam rotates in said opposite direction.

2. In a device of the type described, a dial; means for rotating said dial at a constant speed, a trip arm adjustably secured to said dial for rotation therewith; a cam rotatably mounted for movement about an axis; a bridge mounted for movement about said axis, said cam and said bridge being connected for simultaneous movement in one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite direction, said recess having a camming surface to move said lever back to non-actuated position as said cam rotates in said opposite direction; and means for retarding the movement of said cam in said opposite direction.

3. A time control device for actuating a switch having a lever comprising, an operating cam and a bridge mounted in side by side relation for independent rotatable movement about a common axis, said cam and said bridge having arcuate peripheral surfaces, the peripheral surface of said bridge extending arcuately outwardly beyond the arcuate peripheral surface of said cam, said cam having a recess providing a camming surface a portion of which is disposed inwardly of said arcuate peripheral surfaces; means biasing said cam and bridge in one direction, said cam and bridge being connected for simultaneous movement in the opposite direction; and means for rotating said cam a predetermined distance in said opposite direction, said lever riding over said peripheral surface of said bridge as said cam rotates in said opposite direction, said lever moving into said recess and into actuated position as said cam is released for movement in said opposite direction and preventing movement of said bridge in said opposite direction, said camming surface of said recess moving said lever out of actuated position and out of said recess as said cam moves in said opposite direction to free said bridge for movement in said opposite direction.

4. A time control device for actuating a switch having a lever comprising, an operating cam and a bridge mounted in side by side relation for

independent rotatable movement about a common axis, said cam and said bridge having arcuate peripheral surfaces, the peripheral surface of said bridge extending arcuate outwardly beyond the arcuate peripheral surface of said cam, said cam having a recess providing a camming surface a portion of which is disposed inwardly of said arcuate peripheral surfaces; means biasing said cam and bridge in one direction, said cam and bridge being connected for simultaneous movement in the opposite direction; means for rotating said cam a predetermined distance in said opposite direction, said lever riding over said peripheral surface of said bridge as said cam rotates in said opposite direction, said lever moving into said recess and into actuated position as said cam is released for movement in said opposite direction and preventing movement of said bridge in said opposite direction, said camming surface of said recess moving said lever out of actuated position and out of said recess as said cam moves in said opposite direction to free said bridge for movement in said opposite direction; and means for retarding the movement of said cam in said opposite direction.

5. The device of claim 3 characterized in that said means for moving said cam in said opposite direction comprises a rotatable dial, a trip arm adjustably secured on said dial, said trip arm engaging said cam to move it a predetermined distance in said opposite direction as said dial is rotated.

6. A time control device for actuating a switch having an operating lever comprising, a cam and a bridge mounted in side by side relation for independent rotatable movement about a common axis, said cam and said bridge having arcuate peripheral surfaces, the peripheral surface of said bridge extending arcuately outwardly beyond the arcuate peripheral surface of said cam, said cam having a recess providing a camming surface a portion of which is disposed inwardly of said arcuate peripheral surfaces; means biasing said cam and bridge in one direction, said cam having an arcuate slot; means on said bridge extending through said slot whereby said bridge is moved by said cam in the opposite direction when said cam is moved in said opposite direction; and means for rotating said cam a predetermined distance in said opposite direction, said lever riding over said peripheral surface of said bridge as said cam rotates in said opposite direction, said lever moving into said recess and into actuated position as said cam is released for movement in said opposite direction and preventing movement of said bridge in said opposite direction, said camming surface of said recess moving said lever out of actuated position and out of said recess as said cam moves in said opposite direction to free said bridge for movement in said opposite direction.

7. A time control device for actuating a switch having an operating lever comprising, a cam and a bridge mounted in side by side relation for independent rotatable movement about a common axis, said cam and said bridge having arcuate peripheral surfaces, the peripheral surface of said bridge extending arcuately outwardly beyond the arcuate peripheral surface of said cam, said cam having a recess providing a camming surface a portion of which is disposed inwardly of said arcuate peripheral surfaces; means biasing said cam and bridge in one direction, said cam having an arcuate slot; means on said bridge extending through said slot whereby said bridge

is moved by said cam in the opposite direction when said cam is moved in said opposite direction; means for rotating said cam a predetermined distance in said opposite direction, said lever riding over said peripheral surface of said bridge as said cam rotates in said opposite direction, said lever moving into said recess and into actuated position as said cam is released for movement in said opposite direction and preventing movement of said bridge in said opposite direction, said camming surface of said recess moving said lever out of actuated position and out of said recess as said cam moves in said opposite direction to free said bridge for movement in said opposite direction; and means for retarding the movement of said cam in said one direction.

8. The device of claim 6 characterized in the said means for moving said cam in said opposite direction comprises a rotatable dial, a trip arm adjustably secured on said dial, said trip arm engaging said cam to move it a predetermined distance in said opposite direction as said dial is rotated.

9. In a device of the type described, a dial; means for rotating said dial at a constant speed, a trip arm adjustably secured to said dial for rotation therewith; a cam rotatably mounted for movement about an axis; a bridge mounted for movement about said axis; said cam having a slot; means on said bridge extending into said slot whereby said bridge is moved by said cam in one direction when said cam is moved in said one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite position, said recess having a camming surface to move said lever back to non-actuated position as said cam rotates in said opposite direction.

10. In a device of the type described, a dial; means for rotating said dial at a constant speed, a trip arm adjustably secured to said dial for rotation therewith; a cam rotatably mounted for movement about an axis; a bridge mounted for movement about said axis; said cam having a slot, means on said bridge extending into said slot whereby said bridge is moved by said cam in one direction when said cam is moved in said one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite position, said recess having a camming surface to move said lever back to non-actuated position as said cam rotates in said opposite direction.

11. In a device of the type described, a dial; means for rotating said dial at a constant speed, a trip arm adjustably secured to said dial for rotation therewith; a cam rotatably mounted for movement about an axis; a bridge mounted for movement about said axis, said cam having a slot; means on said bridge extending into said slot whereby said bridge is moved by said cam in one direction when said cam is moved in said one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite position, said recess having a camming surface to move said lever back to non-actuated position as said cam rotates in said opposite direction.

12. In a device of the type described, a dial; means for rotating said dial at a constant speed, a trip arm adjustably secured to said dial for rotation therewith; a cam rotatably mounted for movement about an axis; a bridge mounted for movement about said axis, said cam and said bridge being connected for simultaneous movement in one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite position, said recess having a camming surface to move said lever back to non-actuated position as said cam rotates in said opposite direction; gear teeth on said cam; and a pinion gear on a weighted wheel meshing with said gear teeth whereby the inertia of said wheel retards the movement of said cam in said opposite direction.

13. In a device of the type described, a dial; means for rotating said dial at a constant speed, a trip arm adjustably secured to said dial for rotation therewith; a cam rotatably mounted for movement about an axis; a bridge mounted for movement about said axis, said cam and said bridge being connected for simultaneous movement in one direction; means biasing said cam and said bridge in the opposite direction; a switch having an operating lever normally held in inoperative position by said cam and said bridge, said trip arm engaging and rotating said cam a predetermined distance in said one direction as said dial is rotated, said cam having a recess, said bridge causing said lever to ride over said recess as said cam is rotated in said one direction, said recess allowing said lever to move to actuated position as said cam rotates back in said opposite direction, said lever when in said actuated position preventing movement of said bridge in said opposite position, said recess having a camming surface to move said lever back to non-actuated position as said cam rotates in said opposite direction; gear teeth on said cam; and a pinion gear on a weighted wheel meshing with said gear teeth whereby the inertia of said wheel retards the movement of said cam in said opposite direction.

14. A time control device for actuating a switch having an operating lever comprising a cam and a bridge mounted in side by side relationship for independent rotatable movement about a common axis, said cam and bridge being connected for simultaneous movement in one direction about said axis; means biasing said cam and said bridge in the opposite direction, said operating lever being normally held in inoperative position by said cam and said bridge; means for rotating said cam a predetermined distance in said one direction, said cam having a recess, said bridge causing said lever to ride over said

recess as said cam is rotated in said one direction, said bridge allowing said lever to move to actuated position as said cam rotates back in said opposite direction, said lever when in actuated position preventing movement of said bridge in said opposite direction, said recess having a camming surface to move said lever back to non-actuated position as said cam rotates in said opposite direction.
